STEPLADDER

Henry Harrison, Port Washington, N. Y.

Application January 5, 1951, Serial No. 204,550

7 Claims. (Cl. 228—31)

1

My invention relates generally to a step ladder construction having a main body portion, rearwardly extendable bracing legs, and operating linkage systems for controlling the folding movements of the same. In particular, I am concerned with such a step ladder construction wherein novel linkage systems are provided for simultaneously moving the bracing legs laterally and rearwardly with respect to the body portion of the structure so that the area of the base on which the ladder rests is substantially increased.

It is well known that step ladders of conventional design with bracing legs, whose base width is equal to the base width of the main body portion are unsafe for use on rough ground because they can so easily fall over sideways. Furthermore, when the ladder becomes worn, the joints get loose and it becomes unsafe for use on level supporting surfaces.

Therefore, the primary object of my invention is to improve the stability of step ladders by providing means for simultaneously and in a single motion extending the bracing legs laterally as well as rearwardly of the main body portion so that the width of the base on which the ladder rests is substantially increased.

Another object of my invention is to provide a step ladder construction of the type described above, possessing increased stability over conventional forms of step ladder constructions which is strong and rigid in the vertical direction and having stiffness against torsional and shearing strains.

A further object of my invention is to provide operating linkage systems for ladders of this type including hinged frames defining substantially rigid planes adapted to positively control the motion of the bracing legs during ladder opening and folding movements and to maintain the bracing legs in a fixed position relative to the main ladder portion when the ladder is in open or operative position.

Another object of my invention is to construct a ladder which may be efficiently and safely employed either as a step ladder or as an ordinary ladder.

A still further object of my invention is to provide a step ladder construction of the type described above made of either wood or metal having operating linkage systems whereby the foot portions of the bracing legs fold to a position substantially above the plane of the ends of the uprights of the body portion of the structure, whereby the bracing legs do not engage the supporting surface as the ladder structure is leaned against an object to be scaled.

Another object of my invention is to provide a step ladder construction including novel operating linkage systems which may be easily fabricated from either wood or metal, and which will be light in weight, strong and rigid in use and yet inexpensive in manufacture.

2

With these and other objects in view, the invention consists in certain novel features of construction and combinations and arrangements of parts which will be more fully described and pointed out in the claims.

In the accompanying drawings:

Figure 1 is a perspective view of a metallic step ladder shown in the fully extended position and embodying my invention.

Figure 1a is a sectional view of a step element of my ladder structure.

Figure 2 is a perspective view of the same step ladder in a partially folded position illustrating the folding action of the operating linkage systems.

Figure 3 is a perspective view of the same ladder in the completely folded position.

Figure 4 is a diagram illustrating the essential steps of designing the operating linkage systems of my invention.

Figure 5 is a perspective view of a ladder utilizing wooden construction illustrating a modified form of operating linkage systems employed therewith.

Figure 6 is an isometric perspective view of the same ladder and linkage systems illustrated in part in Figure 5, illustrating the manner in which the modified linkage systems bring the bracing legs together with their lower ends somewhat above the plane of the ends of the uprights of the ladder position of the structure.

Figure 7 is a perspective view of a bracing leg hinge bracket suitable for use with wooden step ladder constructions.

Figure 8 is a view in elevation showing the bracket of Figure 7 in position.

The body portion of the step ladder of my invention as shown in Figure 1 may be of conventional design. Steps 1 of tubular construction are riveted or otherwise secured to channel uprights 2 and 2' forming a ladder portion which is strong and rigid in the vertical direction and stiff against torsional strains. To further increase the body portion's stiffness in torsion and in shear, a platform 3 and a pivot hinge bracket 4 are secured to the same. A corner of platform 3 has been broken away in this view so that part of the bracket 4 may be seen.

I have found that the substitution of extruded tubing of parallelogram section shown in Figure 1a for the extruded channel now in common use as steps in the body portions of step ladder construction, results in a very large increase in torsional rigidity. The addition of web portions 50 and 51 to the channel webs 52, 53 and 54 provide a step element, possessing great strength which substantially eliminates all twisting and warping of the body portion of my ladder structure.

Separate bracing legs 5, 5', shown in tubular form replace the conventional brace unit found in previous step ladder construction and are joined by hinge rivets 6, 6' to the bracket 4.

shown in more detail in Figure 4 wherein the platform 3 has been removed.

Legs 5, 5' are further secured to the ladder portion uprights 2, 2' by two novel linkage systems, hereinafter described in detail. The first linkage system utilizes linkage frames D and E wherein the linkage frame D consisting of links 7 and 8 turns about pins 9 with respect to links 10 and 11 and cross brace 12 of a second linkage frame E. Linkage frame D joins leg 5 at hinge rivet 13, while linkage frame E joins upright 2 at hinge rivet 14. When the ladder is in extended position, the triangular linkage frames D and E, by hinge pin 9, positively control the relative motion between the main portion of the ladder and the bracing leg 5. On the opposite side of the ladder a triangular linkage frame F, similar to triangular frame D, is formed by links 7', 8' and pin 9' and is also hinged to the operating frame E by the hinge pin 9'. The frame E is formed of links 10, 10'; 11, 11'; and cross brace 12, and comprises an irregular shaped rigid plane member connected to the body portion uprights 2 and 2' by angle brackets 17, 17' and hinge rivets 14, 14'.

Hinge pins 9 and 9' are provided with short collars 15, 15' and 16, 16' which prevent links 7, 7' and 8, 8' from sliding together or apart along their respective pins 9, 9'. The cross brace 12, forming a strengthening member for frame B and shown of tubular construction, passes through suitable holes in the links 11, 11' and is flattened, bent, and riveted to the links 10, 10' at its ends, as shown in Figure 1. This cross bar 12 maintains the links 10, 10' and 11, 11' in a rigid plane and provides a convenient handle for closing the ladder. Angle brackets 17, 17' are interposed between links 10, 10' and 11, 11' and respective hinge rivets 14, 14', which pivotally connect operating frame E to the uprights 2 for reasons which will be subsequently explained.

In the extended position of the ladder structure, the operating linkage frames D, E and F lie in substantially the same plane and to insure this relationship, a cord or chain 18, joining the intersection of braces 11, 11' and a hole 19 in the edge of one of the steps 1 is provided which prevents the linkage frame from bending downward and thus holds the frames substantially in a rigid plane when the ladder is open. It will be seen in referring to Figure 1, that the force of gravity operating on the linkage frames, securely locks and positively holds the bracing legs in their extended operative position.

In referring to Figure 2, the movements of the bracing legs is along arcuate curves 20 and 20' as the same pass to and from the open and closed positions of the ladder.

A desirable feature found on conventional step ladders is a shelf extension for holding paint cans or tools for convenient use, and this feature might be provided as shown in Figure 1 in which the fulcrum 21 of the shelf passes through holes 22 in the upper portion of the legs 5 and 5', which holes are of sufficiently large diameter as to compensate for the angular changes between the bracing legs and the shelf fulcrum 21. In securing, the ends of the fulcrum 21 may be provided with any suitable means, as peening, to prevent the same from slipping through the holes 22 to become disarranged. The shelf itself may be of conventional design having a substantially rectangular pan 23 and 75

two brace extensions 24 extending under the edge of one of the steps 1.

The effective base of this ladder is bounded by the dotted line 25, illustrated in Figure 1, wherein the base width of the bracing legs is much greater than the space between the uprights 2 of the ladder portion of the structure while the distances of bases 26 and 27 remain substantially equal. In this manner of construction, the step ladder is less inclined to tip over sideways than ladders of conventional design, and the precise proportions of the base are determined by the proportions of the linkage system frames D, E and F. I have found the proportions shown in Figure 1 to be very practical and to be sufficiently stable for safe use on rough ground or other supporting surfaces.

In the folding of the ladder, the linkage frame members assume various positions as they turn about the hinge pins 9, 9' and the pivot pins 13, 13' and 14, 14'. An intermediate position is illustrated in Figure 2.

The motion indicated in Figure 2 and continued to the position shown in Figure 3, is possible without deforming any of the parts if the extended axis of the hinge rivets 6', 13', and 14' and hinge pin 9' all intersect at a common point, indicated at 28' and the extended axis of the hinge rivets 6, 13, and 14 and hinge pin 9, all intersect at a similar point 28 not shown in the drawing. The respective points of intersection of the axes 28 and 28' will be situated, as indicated, on opposite sides of the step ladder structure and must lie on a straight line 29 passing through the axes of the hinge rivets 14 and 14'. Small deviations of the angular relation of the axis such as might exist because of necessary tolerances in manufacture, result only in small deformations of the parts and do not significantly affect the ease of operation or physical shape of the linkage elements. It will thus be seen that the main ladder portion, the bracing legs, and the linkage frames D, E, and F, constitute two separate linkage systems. The first linkage system consists of the ladder upright 2, the ladder bracing leg 5 and linkage frames D and E, pivoted at points 6, 13, 14 and on hinge pin 9. The axes of the hinge rivets and pin of this system, when projected, intersect at the common point 28. The second operating system consists of the main ladder upright 2', bracing leg 5' and linkage frames E and F, pivoted at points 6', 13', 14' and on hinge pin 9'. The axes of these pivot pins and hinge pin 9, when projected, intersect at the point 28', as indicated in Figures 2 and 4.

Figure 3 is a view of the ladder completely folded, wherein the bracing legs 5, 5' are drawn up against the uprights 2, 2' and the linkage frame members D, E and F fold about the respective hinge pins 9, 9' and lie substantially flat against the plane of the uprights 2, 2'. It is now clear that the angle brackets 17, 17' permit links 10, 10' and 11, 11' to turn up into this closed position while the hinge rivets 13 and 14 and hinge rivets 13' and 14' remain separated so that the linkage frame does not accidentally become locked at dead center when the ladder is closed.

Figure 4 illustrates the geometrical method of laying out suitable frame systems for such a step ladder as illustrated and is in the plane of the linkage frame E. When the ladder is in extended condition the linkage frame members D and F are also substantially in the plane of this figure. Points A' and B' illustrate the extended and folded positions respectively of the hinge rivet

13' and leg 5' and point C' indicates the position of the hinge rivet 14' on the ladder upright. Of course, similar points A, B and C are utilized in determining the geometrical lay-out of the linkage frame D and its operating relation to the linkage frame E.

As a first step, line 30 is drawn joining the points A' and B', then a perpendicular bisector 31 of the line 30 is erected. This line 31 found by swinging arcs 32 about points A' and B' is the line about which the linkage frames must fold in order to carry hinge rivet 13' from point A' to point B', and it is, therefore, the axis of hinge pin 9'. The intersection of line 30 and a line 29 through the points C, C' is point 33, and the axis of hinge rivet 13' must be made to pass through this position. In locating the axis of hinge rivet 6 (see Figure 2), a plane determined by the hinge rivet 6 and the axis of hinge rivet 13 and a plane determined by the hinge rivet 6 and the axis of hinge rivet 14 intersect and are formed to have two fixed points 6 and 28 in common. Therefore, these planes have a line in common about which they fold and this line should be made the axis of hinge rivet 6.

It is clear from the foregoing account how one can determine the axes of the various hinges of the linkage systems of this ladder, and it is to be understood that a similar procedure is employed in laying out both of the operating linkage systems.

The design of the linkage systems including the frames D, E and F, the uprights 2 and 2' and bracing legs 5 and 5' support these axes properly within the space limitations and can easily be carried out by anyone skilled in the art. However, it is necessary that the three separately cross hatched linkage frames D, E and F of Figure 4 be rigid surfaces hinged at 9 and 9'.

In order to facilitate the use of the step ladder as an ordinary ladder and adapt the improved linkage systems to wooden ladder construction, certain modifications should be made in the linkage frames D, E and F as well as the pivotal connection of the bracing legs 5, 5' with the main ladder portion.

In the modification shown in Figures 5, 6, and 7, metallic parts of the ladder structure of Figures 1, 2, and 3 have been replaced by wooden parts wherein the uprights 102, 102', steps 101, 101', the top step 103, 103' and bracing legs 105 and 105' are made of solid wood. Preferably, the linkage frames and the hinges are made of metal as it has superior properties for forming and machining and because it can be made strong and yet remain relatively light in weight. To further decrease weight and yet retain strength, the links of the linkage frame members may be constructed of some suitable metal, such as Duralumin. Links 108, 108', as indicated in Figure 5, corresponding to links 8 and 8' of Figure 1, should be constructed with sufficient strength to resist bending forces as well as axial loads, because in this design, the links 107 and 107', corresponding to links 7 and 7' of Figure 1, are joined at intermediate points rather than at the hinge rivets 113 and 113'. These links 108 and 108' should, therefore, be constructed of a solid bar, a deeply formed channel member or preferably a tube made of Duralumin. The primary purpose of these modified linkage frames D', E' and F' illustrated in Figures 5, 6, and 7 is to bring the bracing legs 105 and 105' together at their lower ends at a point substantially above the plane of the lower ends of the ladder uprights

102 and 102' as the ladder is moved to its closed position, as shown in Figure 6. The particular configuration and proportions of the link elements used in the modified linkage frames D' and F' permit links 107, 107' and 108, 108' to fold about hinge pins 109, 109' and to lie substantially in the same plane as the link elements of linkage frame E' as the ladder is folded to closed position. In addition, the bracing legs 105 and 105' may move inwardly without binding against adjacent links of the linkage frames D', E' and F'. The dotted line 140 represents the intersection of the plane of the bottoms of the uprights 102, 102' and the outer surface of the legs 105 and 105'. The clearance 141 indicated in Figure 6, facilitates the use of the ladder as an ordinary ladder and prevents the bracing legs from engaging the floor or supporting surface as the ladder is leaned against an object to be scaled.

It will be seen that the linkage frame modification illustrated in Figures 5 and 6, does not depart from the general type of linkage frames illustrated in Figures 1-4 and these modified forms may be designed by the same method. It is only necessary that the frames D', E' and F' form rigid members supporting the axis of hinge rivet 113 in constant spaced and angular relation to the axis of hinge rod 109.

In the modified form of the invention, the hinge connections of the bracing legs and body portion of the ladder have been altered in a manner suitable for wooden-type step ladder construction and only the pivot connection of brace leg 105 to upright 2 will be discussed in detail. Referring to Figures 6, 7, and 8, brace leg 105 is capped by a metal strap 150 attached to the same by rivets 151. This strap is bent to a roof shape so that one oblique surface makes bearing contact with a plane surface 152 of a modified hinge bracket 104, illustrated in detail in Figure 7 and shown in position in Figure 8.

Hinge bracket 104 is constructed of a plane piece of sheet metal such as Duralumin or steel by simply bending a pre-cut blank. In this manner, a plane bearing surface 152 bent from the plane of the blank along the line 154 is made normal to the hinge axis 106 about which leg 105 swings. As explained in connection with the ladder of Figures 1, 2, and 3, this hinge axis must pass through the intersection of the axis of the hinge rivet 114, hinge pin 109 and hinge rivet 113, in order that the ladder may open or close without deformation of the structural parts. The portion of the bracket 104 which is turned back to form plane surface 152 is continued and forms a brace 153 by a simple bend along the lines 155 and 157. Another bend along the line 156 serves to turn parts of the bracket 104 into the plane of the bottom of the top step 103 of the body portion of the ladder. In joining the bracket 104 to the cap strap 150 of the bracing leg 105 a hinge rivet 106 passes through holes in the corresponding oblique plate surfaces of these parts and is secured, as by peening, to hold the surfaces together. Rivets 158 passing through the holes 159 in the hinge bracket fasten the bracket 104 to the uprights member 102 and to the top step 103. Thus, the bracket 104, in addition to its function as a hinge member, also serves as a bracket to join the top step 103 to the upright member 102.

A second hinge bracket 104', the mirror image of bracket 104, is also required for the pivotal connection of bracing leg 105' to the upright 102'.

A second cap strap 150', similar in shape to cap strap 150 completes the pivotal connection.

The chain 18, disclosed in Figures 1, 2, and 3, has been omitted in the modified form of my step ladder construction, and in Figures 5 and 6 linkage frames D', E' and F' are maintained substantially within the same plane when the ladder is in its open position by links 110, 110' and 111 and 111' resting against the top of one of the adjacent steps 101. It will thus be seen that the linkage frame members are positively prevented from passing downward to an inoperative position.

In this form of my step ladder construction, the shelf extension for holding paint cans or the like, may also be utilized. This feature has been omitted in Figures 5, 6, and 7. However, it may be conveniently installed, if provision is made in the bracing legs 105 and 105' for slidably and pivotally receiving the fulcrum pin 21 of the shelf structure.

In addition to the foregoing, I may modify my linkage frame systems so as to allow the bracing legs 105 and 105' to actually cross. This arrangement of the bracing legs 105 and 105' would not depart from the substance of my invention, although it might then be desirable to attach the linkage frames to the outside of the bracing legs rather than the inside, as is shown in these drawings.

Metallic ladders of the type shown and described may be made of any light weight rigid metallic materials. However, I have found magnesium, magnesium alloys and Duralumin type metals are particularly adapted for light weight step ladder constructions.

I claim:

1. In a step ladder construction as herein described, a body portion comprising a pair of laterally spaced apart upright members having a plurality of vertically spaced horizontal step elements secured at their respective ends to the upright members, a pair of rearwardly disposed ladder bracing legs each pivotally fastened to the upper portion of one of said upright members, and means for simultaneously moving the bracing legs laterally and rearwardly of the body portion of the ladder and for securely holding the bracing legs fixed when the ladder is in its extended position comprising a plurality of rigid operating frames including a primary frame element, a pair of secondary frame elements hinged to said primary frame element for folding movement with respect to the same, said primary frame having pivotal connection to the body portion of the step ladder and said secondary frames each having pivotal connection to a respective bracing leg.

2. A step ladder construction, as set forth in claim 1, wherein the primary frame engages a step element as the ladder is unfolded to its open position to maintain the operating frames substantially within a plane.

3. In a step ladder construction as herein described, a body portion comprising a pair of laterally spaced apart upright members having a plurality of vertically spaced horizontal step elements secured at their respective ends to the upright members, a pair of rearwardly disposed ladder bracing legs each pivotally fastened to the upper portion of one of said upright members, and means for simultaneously controlling the rearward and lateral movement of said bracing legs comprising rigid operating frames composed of a plurality of link bars wherein a pair of sec-

ondary frame elements are hinged to a primary frame element along non-parallel lines for folding movement with respect to the same, said primary frame having pivotal connection to the body portion of the step ladder and said secondary frames each having pivotal connection to a respective bracing leg.

4. In a ladder construction as set forth in claim 3 wherein a plurality of hinged rigid frame elements controlling movements of the bracing legs with respect to the body portion of the step ladder lie substantially within a plane when the ladder is in extended position.

5. In a ladder construction as set forth in claim 3 wherein flexible means are provided for maintaining the rigid frame elements substantially within the same plane when the ladder is in its extended position.

6. In a step ladder construction as herein described, a body portion comprising a pair of laterally spaced apart upright members having a plurality of vertically spaced horizontal step elements secured at their respective ends to the upright members, a pair of rearwardly disposed ladder bracing legs each pivotally fastened to the upper portion of one of said upright members, and means for simultaneously controlling the rearward and lateral movements of said bracing legs comprising a pair of linkage systems, each of said systems including one of said ladder upright members, its respective bracing leg, a rigid triangular operating frame and a second operating frame common to said operating systems wherein the pivot axes of the elements of the systems when extended intersect at common points spaced laterally of the ladder body and on a line passing through the axes of the pivot connection of said second operating frame to the ladder upright members.

7. In a step ladder construction as herein described, a body portion comprising a pair of laterally spaced apart upright members having a plurality of vertically spaced horizontal step elements secured at their respective ends to the upright members, a pair of rearwardly disposed ladder bracing legs each pivotally fastened to the upper portion of one of said upright members, and means for simultaneously controlling the rearward and lateral movements of said bracing legs comprising rigid operating frames composed of a plurality of link bars wherein a pair of secondary frame elements are hinged to a primary frame element along non-parallel lines for folding movement with respect to the same, said primary frame having pivotal connection to the body portion of the step ladder and said secondary frames each having a rigid link bar extending beyond the confines of its frame and pivotally connected to the respective bracing leg whereby the bracing legs in the ladder folded position come together toward their lower ends at a point above the plane of the ends of the upright members so that the bracing legs will clear a ladder supporting surface when the ladder is leaned against an object to be scaled.

HENRY HARRISON.
